UNITED STATES PATENT OFFICE.

ALBERT LEGRAND, OF PARIS, FRANCE

BODY FOR MOTOR ROAD-VEHICLES.

1,142,590.

Specification of Letters Patent.

Patented June 8, 1915.

Application filed November 20, 1913. Serial No. 802,065.

To all whom it may concern:

Be it known that I, ALBERT LEGRAND, a citizen of the Republic of France, residing at Paris, in France, have invented a new and useful Body for Motor Road-Vehicles, of which the following is a specification.

This invention has for its object a body of the torpedo type for motor road vehicles which permits of dispensing with the wooden beams that are generally fitted to the chassis for supporting the overhanging portion of the body.

The invention consists in fixing to the ordinary chassis a projecting band or girdle constituted by an iron member connected with the longitudinal members of the said chassis by means of stays. The body rests upon the chassis thus constituted, its transverse curvature merging with that of the 20 lower gear case; the longitudinal elements of the chassis are also concealed and no portion of the mechanism is visible.

Various embodiments of the invention are illustrated by way of example in the accompanying drawing, in which:

Figure 1 is a side elevation of one embodiment of the invention. Fig. 2 is a plan thereof. Fig. 3 is a diagrammatic cross-section, and Fig. 4 shows a modified construction in plan.

In Figs. 1 to 3, the metal band *a* is united with the longitudinal elements *b* of the chassis by stays *c* and at the rear it is connected by stays *c* with the transverse member *d*. The result of this arrangement is that with a band thus constituted and arranged at the proper distance from the members of the chassis, it is possible to fit a body *e* in such a manner that its overhang is efficiently supported and which is given a good bearing without the employment of the wooden beams ordinarily interposed between the top of the chassis and the bottom of the body.

The lower gear case *f* is curved in such a manner that it follows on and continues the curve constituted by the outer wall of the body *e* as shown in Fig. 3. The two longitudinal members of the chassis, are also concealed, whereby the appearance of the vehicle is improved. As shown in Fig. 4, the same result can be obtained while dispensing with a portion of the band. In this ar-

rangement, the metal band *a* united with the longitudinal members *b* by the stays *c* is omitted at the rear portion of the chassis, 55 which, in this case itself presents the rounded form that was constituted by a portion of the band. In this embodiment of the invention it is preferable to form the chassis proper in two parts which are assembled at 60 the rear by any convenient means. The same result can be attained by dispensing entirely with the fitted band and giving the longitudinal members of the chassis a form corresponding to that of the body in such 65 a manner that the chassis is widened in order to support the overhang of the body.

Another embodiment of the invention consists in forming the chassis in a single piece by means of a stamped plate, the outer periphery of which exactly corresponds with 70 that of the body.

The rear axle suspension springs *g* can be arranged either outside the chassis as represented in Figs. 1 and 2, or inside the chassis as shown in Fig. 4.

What I claim is:

1. In a motor road vehicle, the combination with a chassis, of a projecting metal band, stays connecting said band with the 80 longitudinal members of the chassis, a body resting upon said band and being curved, and a lower curved gear case forming a continuation of the curve of the body.

2. In a motor road vehicle, the combination with a chassis, the longitudinal members of which at the rear are joined by a curved portion, of a projecting metal band, stays connecting said band with the longitudinal members of the chassis, a body resting upon said band and being curved at the rear to correspond with the curvature of the said curved portion joining the longitudinal chassis members, and also being curved at the sides, and a lower curved gear 95 case forming a continuation of the curve of the sides of the body.

In testimony whereof I affix my signature in presence of two witnesses.

ALBERT LEGRAND.
